(57) **CLAIM**

The ornamental design for furniture as shown and described.

DESCRIPTION

FIG. 1 is a front view illustrating my design for furniture; FIG. 2 is a left view thereof;

FIG. 3 is a right view thereof;

FIG. 4 is a rear view thereof;

FIG. 5 is a top view thereof;

FIG. 6 is a bottom view thereof; and

FIG. 7 is a perspective view thereof;

FIG. 8 is a front view illustrating another embodiment of my design for furniture;

FIG. 9 is a left view thereof;

FIG. 10 is a right view thereof;

FIG. 11 is a rear view thereof;

FIG. 12 is a top view thereof;

FIG. 13 is a bottom view thereof; and

FIG. 14 is a perspective view thereof;

FIG. 15 is a front view illustrating another embodiment of my design for furniture;

FIG. 16 is a left view thereof;

FIG. 17 is a right view thereof;

FIG. 18 is a rear view thereof;

FIG. 19 is a top view thereof;

FIG. 20 is a bottom view thereof; and

FIG. 21 is a perspective view thereof;

FIG. 22 is a front view illustrating another embodiment of my design for furniture;

FIG. 23 is a left view thereof;

FIG. 24 is a right view thereof;

FIG. 25 is a rear view thereof;

FIG. 26 is a top view thereof;

FIG. 27 is a bottom view thereof; and

FIG. 28 is a perspective view thereof.

The broken lines shown in the drawings illustrate portions of the article that form no part of the claimed design.

1 Claim, 28 Drawing Sheets
